(57) **CLAIM**

The ornamental design for cargo tie-down rails, as shown and described.

DESCRIPTION

FIG. 1 is a plan view of a pick-up truck drawn in phantom and a pair of tie-down cargo rails showing my new design.

FIG. 2 is a side view of the pick-up truck and pair of tie-down cargo rails.

FIG. 3 is an enlarged cross-sectional view taken on the line 3—3 in FIG. 2.

FIG. 4 is an enlarged front view of one of the tie-down cargo rails.

FIG. 5 is an enlarged broken plan view of the tie-down cargo rail.

FIG. 6 is an enlarged broken front view of the tie-down cargo rail.

FIG. 7 is an enlarged end view of the tie-down cargo rail; and,

FIG. 8 is an enlarged rear view of the tie-down cargo rail. The broken line showing of environment is for illustrative purposes only and forms no part of the claimed design.

FIGS. 5, 6 and 8 are shown broken away for ease of illustration.
